UNITED STATES PATENT OFFICE.

PETER J. PETERSON, OF CHUGWATER, WYOMING.

TRAP.

Application filed December 2, 1924. Serial No. 753,489.

To all whom it may concern:

Be it known that I, PETER J. PETERSON, a citizen of the United States, residing at Chugwater, in the county of Platte and 5 State of Wyoming, have invented certain new and useful Improvements in Traps, of which the following is a specification, reference being had to the accompanying drawings.

10 This invention relates to certain improvements in traps and has relation more particularly to a device of this general character of an impaling or striking type and wherein the set striking member is released 15 by the weight of the victim.

Another object of the invention is to provide a device of this general character comprising a striking member maintained in set position by a latch mechanism, said latch 20 mechanism being released upon weight being imposed upon a movable member properly positioned with respect to the striking member.

Furthermore, it is an object of the invention 25 to provide a device of this general character wherein a latch mechanism operates to maintain a striking member in set position together with a platform supported for rocking movement and over which the victim is 30 adapted to pass, said platform being operatively connected with the latch mechanism in a manner whereby depression of either end portion of the platform will effect a release of the latch mechanism with respect to 35 the striking member.

The invention consists in the details of construction and in the combination and arrangement of the several parts of my improved trap whereby certain important advantages are attained and the device rendered simpler, less expensive and otherwise 40 more convenient and advantageous for use, as will be hereinafter more fully set forth.

The novel features of my invention will 45 hereinafter be definitely claimed.

In order that my invention may be the better understood, I will now proceed to describe the same with reference to the accompanying drawings, wherein:—

50 Figure 1 is a view in perspective illustrating a trap constructed in accordance with an embodiment of my invention with a second position of the striking member indicated by broken lines;

Figure 2 is a view in end elevation of the 55 structure as illustrated in Figure 1;

Figure 3 is a view in side elevation of the device as illustrated in Figure 1 with a side plate or wall removed;

Figure 4 is a view partly in elevation and 60 partly in section illustrating a further embodiment of my invention;

Figure 5 is a sectional view taken substantially on the line 5—5 of Figure 4;

Figure 6 is a view in perspective of a portion of the latch mechanism as herein disclosed;

Figure 7 is a fragmentary view in perspective of a further form of striking member.

As particularly illustrated in Figures 1, 2 and 3 of the accompanying drawings, my improved trap comprises a runway R of requisite dimensions and which comprises the base plates 1 and the side walls 2 and 3. One of said walls, as 3, being of a height 75 less than the height of the side wall 2. Pivotally connected, as at 4, to the lower marginal portion of the side wall 2 is a longitudinal marginal portion of a striking member M preferably of a length to extend a slight distance beyond the opposite ends 80 of the runway R so that the swinging or lifting of the member M into set position may be easily accomplished.

As disclosed in Figures 1, 2 and 3 the 85 member M constitutes a wire structure although I do not wish to be understood as limiting myself in this respect because said striking member may be otherwise constructed. In Figure 7, I disclose a striking 90 member M' consisting of a plate herein disclosed as provided with openings 5. These openings 5 in addition to lightening the weight of the member M' also serve to provide a more effective grip for holding of the 95 victim. It is to be understood that these openings 5 as also the openings in the member M are relatively small so that there will be no possibility of a victim passing therethrough.

The pivoted marginal portion of the member M has engaged therewith in a conventional manner the springs 6 operating under sufficient tension to throw the striking member M downwardly with sufficient force to 105 kill a victim passing through the runway.

The free longitudinal marginal portion of the member M has disposed laterally

therefrom a loop or hasp 7 of a length to extend through a suitably positioned opening 8 in the wall 2 so that the member M may be held in raised or set position by a suitable latch mechanism.

As herein disclosed, the latch mechanism comprises a vertically disposed lever or trigger 9 pivotally connected at a point in relatively close proximity to its lower end 10 for pivotal movement by the wall 2, such pivotal connection as herein disclosed consisting of a staple member 10.

Supported by the upper portion of the wall 2 for swinging or rocking movement 15 in a vertical direction is a plate 11 having its longitudinal marginal portions provided with the strengthening flanges 12. This plate 11 extends beyond opposite sides of the wall 2 and said plate 11 outwardly of 20 its pivotal mounting 14 is provided with an opening 15 through which is adapted to be disposed the upper end portion of the lever or trigger 9.

The base plates 1 are arranged at the 25 opposite ends of the runway and provide therebetween a central base opening 16 in which is positioned a platform 17, said platform being pivotally connected, as at 18, midway its ends, with the side walls 2 and 30 3 whereby said platform is supported for vertical swinging or tilting movement. Operatively engaged, as at 19, with a side 35 of the platform 17 immediately adjacent the ends thereof are the members 20. As herein disclosed, the members 20 are rods, and each rod is slidably disposed through a side portion of the plate 11 remote from the end of the platform 17 with which it is operatively engaged, such arrangement in the 40 present embodiment of my invention causing the members or rods 20 to have overlapping relation at a point below but in relatively close proximity to the plate 11 as is clearly illustrated in Figures 1 and 3 of 45 the accompanying drawings.

Each of the members or rods 20 above the plate 11 has adjustably mounted thereon a head or enlargement 21, the same being herein disclosed as a winged nut.

When the member M is in its raised or 50 set position and the trigger 9 operatively engaged with the loop or hasp 7 and with the plate 11, the enlargements or heads 21 of both of the members or rods 20 will be 55 in contact with the inner end portion of the plate 11.

As a victim enters the runway and passes 60 upon the platform 17 from either end, the weight of the victim will depress said end portion of the platform resulting in a member or rod 20 operatively engaged with said end portion of the platform to impose a downward pull upon the inner end portion 65 of the plate 11 resulting in the opposite or outer end portion of the plate swinging up-

wardly and free from the trigger or lever 9 whereupon the springs 6 will force the member M downwardly with sufficient impact to strike and hold the victim from above, the blow being generally sufficient to 70 kill the victim.

A trap such as this does not require the use of bait although if preferred the same can be employed. This trapping of the victim is further facilitated by having each of 75 the base plates 1 of such a length as to assure the victim being fully within the runway before passing onto the platform.

In trapping rodents or burrowing animals I find it of especial advantage to employ in connection with my trap the attachment particularly illustrated in Figures 4 and 5 of the drawings. With the use of this attachment the set trap is positioned in 80 relatively close proximity to the opening from which the victim is expected to emerge and my improved attachment is engaged over the adjacent end of the runway and directly above the opening. This attachment constitutes a member 22 of desired dimensions and preferably in the form of an inverted U in cross section and having one 85 end closed by a plate 23. The open end portion of the member 22 is engaged with an end portion of the trap proper as is believed to be clearly shown in Figure 4 of the drawings. This attachment or member 22 constitutes a continuation of the runway 90 R and is used to assure that the victim as he leaves the opening or burrow can only pass 95 out through the runway R.

From the foregoing description it is thought to be obvious that a trap constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as 100 hereinafter claimed.

I claim:

1. A trap comprising, in combination, a runway, a striking member mounted therein, a latch mechanism for holding the striking member in set position, said latch mechanism including a movable member engageable with the striking member, a rock member engageable with the movable member to hold the movable member in engagement with the striking member, a platform within the runway supported intermediate its ends for swinging movement, an operative connection between each end portion of the platform and the rock member to dis-

engage the rock member from the movable member upon movement in one direction of either end portion of the platform, each of said operative connections comprising a rod 5 slidably disposed through the rock member, and an enlargement carried by the rod outwardly of the rock member for contact therewith.

2. A trap comprising, in combination, a runway, a striking member mounted therein, a latch mechanism for holding the striking member in set position, said latch mechanism including a movable member engageable with the striking member, a rock member 15 engageable with the movable member to hold the movable member in engagement with the striking member, a platform within the runway supported intermediate its ends for swinging movements, and members 20 operatively connecting the outer end portions of the platform and the rock member to disengage the rock member from the movable member upon movement in one direction of either end portion of the platform, each of

said members being provided with means 25 for contact with the rock member.

3. A trap comprising, in combination, a runway, a striking member mounted therein, a latch mechanism for holding the striking member in set position, said latch mechanism including a movable member engageable with the striking member, a rock member 30 engageable with the movable member to hold the movable member in engagement with the striking member, a platform within 35 the runway supported intermediate its ends for swinging movement, and members operatively connecting the outer end portions of the platform and the rock member to disengage the rock member from the movable 40 member upon movement in one direction of either end portion of the platform, each of said members being provided with means 45 for contact with the rock member outwardly of said rock member.

In testimony whereof I hereunto affix my signature.

PETER J. PETERSON.
